UNITED STATES PATENT OFFICE.

FOSTER GUNNISON, OF BRONXVILLE, NEW YORK, ASSIGNOR TO COX, NOSTRAND & GUNNISON, INCORPORATED, OF BROOKLYN, NEW YORK, A CORPORATION OF NEW YORK.

DESIGN FOR A MODERNISTIC INDIRECT ELECTRIC LIGHTING FIXTURE.

Application filed December 6, 1928. Serial No. 29,129. Term of patent 14 years.

To all whom it may concern:

Be it known that I, FOSTER GUNNISON, a citizen of the United States, residing in the village of Bronxville, county of Westchester, State of New York, have invented a new and original Design for Modernistic Indirect Electric Lighting Fixtures, of which the following is a specification, reference being had to the accompanying drawing, forming a part thereof, in which—

Fig. 1 is a perspective view of a lighting fixture.

Fig. 2 is a side elevation.

Fig. 3 is a bottom plan view.

I claim:

The ornamental design for a modernistic indirect electric lighting fixture, as shown.

FOSTER GUNNISON.
